US00D532399S

(12) **United States Design Patent** (10) **Patent No.:** **US D532,399 S**
(45) **Date of Patent:** **** Nov. 21, 2006**

(54) **COMBINED DISPLAY AND DISC PLAYER**

(75) Inventors: **Takashi Sogabe**, Tokyo (JP); **Koji Shindo**, Tokyo (JP)

(73) Assignee: **Sony Corporation**, Tokyo (JP)

(**) Term: **14 Years**

(21) Appl. No.: **29/222,345**

(22) Filed: **Jan. 31, 2005**

(51) **LOC (8) Cl. 14-01**

(52) **U.S. Cl. D14/132; D14/129**

(58) **Field of Classification Search** D14/132, D14/135, 136, 156, 157, 167, 168, 125, 129; 455/347, 348, 349, 350, 351, 344, 345, 346; 369/75.1, 75.2, 77.1, 77.2; 720/605, 600, 720/655; 348/836, 838, 180, 184, 325, 739; 341/12

See application file for complete search history.
